[57] CLAIM

The ornamental design for an electrical apparatus enclosure,
as shown and described.

DESCRIPTION

FIG. 1 is a perspective view of an electrical apparatus enclosure, showing our new design;

FIG. 2 is a top plan view thereof;

FIG. 3 is a front elevational view thereof, the rear elevational
view being a mirror image thereof;

FIG. 4 is a bottom plan view thereof; and,

FIG. 5 is a right side elevation view thereof, the left side
elevation view being a mirror image thereof;
